(57) **CLAIM**

The ornamental design for a mounting frame for connectors of data telecommunication cables, as shown and described.

DESCRIPTION

FIG. 1 is a perspective view of a mounting frame for connectors of data telecommunication cables, showing our new design;

FIG. 2. is a top view thereof;

FIG. 3. is a right side view thereof;

FIG. 4. is a left side view thereof;

FIG. 5. is a front view thereof;

FIG. 6. is a rear view thereof; and,

FIG. 7. is a bottom view thereof.

The broken line portion of the figure drawings is included to show unclaimed subject matter within the central shaft of the design and also on the underside corners of the design; subject matter defined with broken line forms no part of the claimed design.
